UNITED STATES PATENT OFFICE.

ELMER E. WALTER, OF SYRACUSE, NEW YORK, ASSIGNOR TO ONONDAGA POTTERY COMPANY,
OF SYRACUSE, NEW YORK, A CORPORATION.

DESIGN FOR A PLATE.

No. 39,728.

Specification for Design.

Patented Dec. 29, 1908.

Application filed September 25, 1908. Serial No. 454,835. Term of patent 7 years.

To all whom it may concern:

Be it known that I, ELMER E. WALTER, a citizen of the United States, residing at Syracuse, in the county of Onondaga and State of New York, have invented a new, original, and ornamental Design for a Plate, of which the following is a specification, reference being had to the accompanying drawing, forming part thereof.

The figure is a plan view of a china or porcelain plate, showing my new design.

I claim:

The ornamental design for a plate, as shown.

ELMER E. WALTER.
